PAPER TUBE MAKING MACHINERY

David C. Spaulding, Jr., Cleveland, Ohio, assignor
to The Standard Oil Company, Cleveland,
Ohio, a corporation of Ohio

Application August 20, 1937, Serial No. 160,029

20 Claims. (Cl. 93—81)

This invention relates to paper tube making machinery, and more particularly mechanism in which the tube structures are formed and intermittently discharged; and it is among the objects of the invention to provide a construction making possible a rapid through-put of convolute wound tubes, with or without special finishing operations as may be desired. Other objects and advantages will appear as the description 10 proceeds.

To the accomplishment of the foregoing and related ends, the invention, then, comprises the features hereinafter fully described, and particularly pointed out in the claims, the following 15 description and the annexed drawings setting forth in detail certain illustrative embodiments of the invention, these being indicative however, of but a few of the various ways in which the principle of the invention may be employed.

In said annexed drawings:

Fig. 1 is a side elevational view, partly in section, showing an embodiment of the invention; Fig. 1a is an enlarged detail elevation, partly in section, of the mandrel; Fig. 1b is a further enlarged section thereof taken on a plane substantially indicated by line Ib of Fig. 1a; Fig. 1c is an enlarged elevation detail of Fig. 1; Fig. 2 is an enlarged vertical section taken on a plane substantially indicated by line II, Fig. 1, and Fig. 2a is a fragmentary detail thereof showing the tabbed driving-connections. Fig. 3 is a similar view, on larger scale, taken on a plane substantially indicated by line III, Fig. 1; and Figs. 4, 5 and 6 are fragmentary details of the latter.

Referring more particularly to the drawings, there is shown a mandrel 2 which has its drive at the left in Fig. 1, and while the driving means may vary in detail as desired it may comprise in general a shaft 3 supported in framing 4 and having gearing G suitably intermittently rotating the mandrel, while the web of cellulose stock or paper w, Fig. 2, is supplied from a stock roll not shown and passed through an adhesive applicator to the winding station on the mandrel. The stock or paper may be any suitable material for such purpose, and most usually kraft, chestnut board, chip-board, etc. for commoner products, or higher grade paper for special products as desired. The web w proceeding through the applicator receives on one side a coating of adhesive 45 picked up and distributed from the pan 8 by the roller 9, and then proceeds over the feed table F to the mandrel. The latter is provided with a gripper 12, and timing thereof being such that the gripper is in open position when opposite the 50 end of the advancing paper web. Suitable grip-

per-operating means may then close the gripper on the fed end, and on the rotation of the mandrel the desired layers are laid up to form a tube, whereupon the cutter 15 which is operated in timed relation by a cam on the machine drive 5 shaft, severs the paper from the web. The gripper-operating means may comprise for instance a pinion 19, Fig. 1b, on a longitudinally-extending shaft 19a within the mandrel and driving shaft 3 and conveniently being hollow. Depending 10 upon the size of the mandrel, whether operating upon large or small tubes, there may be idler pinion connection 18, 18' between the driving pinion 19 and the toothed segment of the gripper 12, the idlers in general being unnecessary for 15 small sized tubes. With such construction, the slight turning movement of the gripper 12 for opening and closing against the coating lip of the mandrel may be imparted by correspondingly slight turning movement of the drive pinion 19. 20 This may for instance involve a camming action in relative rotation for the pinion shaft 19a with respect to the mandrel shaft 3, and upon the latter there may be slidably mounted a sleeve 19b so as to be rotatable with the shaft 3 and being 25 anti-frictionally engaged by operating fork 19e which is reciprocated by engagement by a cam 19c on the shaft 48. Extending outwardly from the pinion shaft 19a is a pin 19d which rides in a transverse slot 19f in shaft 3 and in an angular 30 slot 19g in sleeve 19b, Fig. 1c, such that longitudinal reciprocation of the sleeve 19b causes the pin 19d to relatively slightly turn and correspondingly rotate the pinion 19 in the mandrel in timed relation. The feed-end of the paper web w being 35 glued on its upper surface, proceeds over the guide roller g on the rear end of the feed table f under the detent-finger d which prevents back-slip of the web, the detent-finger being pivotally mounted at its upper end and being slightly longer than the vertical distance to the floor of the table, whereby to allow the paper web to proceed freely in the forward direction, but occasioning a wedging or grabbing by frictional engagement preventive of backward slippage. Forwardly of the 40 detent-finger, the paper web proceeds through a slitter cutter 7, if it be desired to sever the stock here for two tubes instead of one as wound by the mandrel. The slitter knife of course may be omitted when operating to form one longer tube at a time rather than two end to end. Forwardly 45 of the slitter is a feed finger mechanism which may include a frictionally-engaging finger 10a to suitably grasp the paper web, and such finger may advantageously be of resilient character, normally urged downwardly into gripping rela-

tion against the lower fixed finger 10 by a hook-shaped arm 10b pivoted at the rear and having an angular arm 10c from the end of which a tension spring extends to a point of anchorage on the side of the table. The arm 10c being off center with respect to the tension spring occasions the impartation of a downward pressure through the hook-shaped arm 10b when the latter is turned down against the finger 10a, but allowing such hook-shaped arm to be swung back upwardly, when desired, the tension spring then being past center in the other direction and serving to hold the hook out of engagement down on the finger 10a, thereby allowing easy threading of the paper past the finger. It will be understood that the entire table F with the structures which have just been described, is mounted for reciprocative movement back and forth toward and away from the mandrel, the table for instance being conveniently carried on rollers 12 riding on the support framing, and having a limited range of back and forth movement by reason of gudgeons extending into slots 13 in slide extensions below the general level of the table. Reciprocating movement of the table may be provided by a swing-arm 11a connected through an equalizing link to a projection 11 of the table. The swing-arm 11a is secured to a rock shaft 11b, which also has a fixedly-attached lever arm 11c, Fig. 2a, while a lever arm 11e whose one end is pivoted to the framing 11h carries a cam roller 11f in engagement with a cam 11g on the shaft 48. The cam-arm 11e is connected with the rock shaft arm 11c by a link 11d. Thereby, with the turning of the cam raise 11g the cam arm 11e is raised, and the bell-crank system 11c-11a is actuated to thrust the arm 11a and the table rearwardly. On the further turning of the cam 11a, the return spring 11j draws the table again forwardly. With the paper initially threaded through to position to be fed to and be gripped by the mandrel-gripper 12, it is thus far seen that the web is in condition to be fed forwardly through the open cutter 15 and the pull-along dog d. The lower knife 15a of the pair is vertically movable into cutting and open positions by a suitable mechanism for the actuation of the cutter in timed relation with the feed such that the web is severed and the mandrel can complete its wind-up in the predetermined number of turns of body-forming. While the forward end of the paper is thus being held by being drawn forward by the rotating mandrel in its wind-up the feed table F is thrown back to its rear position, the feed dog or dent d sliding back freely over the paper. Then, after the knife 15 has severed the paper for the completion of the tube being wound, the table F is in readiness to be advanced again to carry the projecting end of the web into the mandrel for a new cycle of wind-up. The movable knife 15a may be operated within its guide 15b for instance by a lever 15c, Figs. 1 and 2, actuated through a link 15d by a bell-crank type lever 15e having a follower in cam 15f.

In order to insure a smooth building of the body as wound on the mandrel, the wound-up layers are advantageously compacted down by a roller 20, which is brought into operation by suitable means, as for instance a cam 20a actuating a lever arm 20b which is in the form of a bell-crank lever fulcrumed to the framing and whose other arm 20c is attached to the arm 20d carrying the roller 20. By means of such construction, any slight adjustment necessary may be provided, there being a slot take-up between the arms 20c and 20d, locking bolt 20e in the slot serving to lock the members in the precise angular position.

An ejector collar 25, Fig. 1, axially movable on the mandrel is arranged with a drive such as to push the formed tube to the next position along the mandrel, suitable means for this being for instance a cam 26 operating the lever 27 whose upper end is pivoted to the framing, and a link 28 and another lever 29 pivoted at its lower end connects through a link 30 to the slide 31 which carries the ejector whereby to reciprocate it in timed relation with the rotation of the mandrel. Where desired, the ejector may thus discharge the tubes from the mandrel. Or preferably the arrangement may be such as to advance it to a next stage where the wound-up tube body receives its further surfacing. Particularly where lower grade stock is used for the building of the body, it is desirable to have also means for supplying a cover which may be of suitable high grade or special stock or it may be a label. For this, a feed table 35, Fig. 3, is arranged to receive a stack of the cover sheets, and an adhesive roller is provided for coating at least the tail end of the sheet as it is advanced into winding position, to assure its smooth seam union. The table 35 is arranged to carry a stack of the cut sheets of such special stock as is to be applied for the finishing layer of the cover, and the table is vertically movable so as to present the topmost sheet in suitable position for engagement by the mandrel. A spring 36 for instance may be provided to pull the table into uppermost position while its downward movement may be effected positively by a cam 36g coacting with a cam roller 36h on the pull-arm 36a which is pivoted at one end to the frame, and at its other end engages by slot 36b with a pin 36c on a lever arm 36d operating against a roller 36e at the lower end of the table stem 36i. The height to which the table rises at any given time when cam 36g is turned into its inactive position depends upon the height of the stack of sheets on the top of the table and the guard finger 50 which is carried by the table and coordinates the feed such that the top sheet of the stack is properly presented at each timed cycle. The guard finger 50 is so mounted in the table as to have a ratchet-wise descent. A smoothing roller 40 is arranged to coat for smoothing the applied cover sheet uniformly, and such smoothing roller may be operated by an arm 41, preferably including a take-up adjustment 42, pivoted to a lever 43 which supports the roller 40 from a pivot point of mounting on the frame. The arm 41 may be reciprocated up and down in timed relation with the rest of the machine by suitable means, as for instance a lever 44 pivotally connected at one end 45 to the frame and having its free end arranged for operation through a cam-roller 44a by a cam 44b on shaft 48. The sheets from the table 35 are fed one at a time by each raise bringing the topmost with its advance end in roll-up feed contact with the table body on the mandrel, and guard finger 50 is arranged to normally just contact the tube on the mandrel 2. As the sheets are removed from the stack progressively, the table 35 is correspondingly raised, and the guard finger 50 correspondingly retracts as needed, by its escapement ratchet, which may include a spring pawl 52, coacting with the ratchet toothed stem 53 of the guard finger.

The operation of the machine will be clearly understood from the foregoing. The paper web w fed from its roll is coated with adhesive by the roller 9 and is forwarded to the feed table F and into the gripper 12, the mandrel in its beginning

cycle of rotation, turning, with prompt closure of the gripper, and thence winding the sheet stock into tube form in whatever number of layers is desired. In its travel over the feed table F, it will be understood that the paper web proceeds over the guide roller g past detent d to slitter r, the detent d serving to wedge and hold the paper against back-slacking, and the forward end of the paper web comes between the lower feed finger 10 and the upper feed finger 10a, the finger 10a sliding over the paper web, but frictionally gripping it on forward feeding movement to the mandrel-gripper 12 which by the timing is open at that instant. Being gripped then in the mandrel, the latter then rapidly rotating to two or for instance four or more turns, builds up the desired body thickness, the cutter knife 15a having severed the paper. With further turning of the mandrel, the smoothing roller 20 being mean- time in operation against the paper, the successive layers are laid down and are bonded by the adhesive, to the completed wind-up of the cut portion. Thereupon, the ejector collar 25 is moved forwardly by its slide 31 and associated mechanism and the mandrel gripper 12 is opened, and the mandrel is cleared for the reception of the on-coming end of the advancing paper web as fed by the reciprocating fingers 10, 10a. The tube wound and pushed along by the ejector collar 25 is now in position opposite the table 35, where for instance a stack of cover sheets is in place, and at this juncture the table is raised to feed the top-most sheet to the tube, and since the outside of the wound-up paper constituting the tube is the adhesive-coated side the sheet as raised with its advance end thereagainst adheres and winds onto the rotating tube. The upper position of the table 35 is gauged by guard finger 50 whose functioning prevents feed of more than one thickness of paper to the tube at a time, the guard finger being automatically compensated to the diminishing stack of sheets on the table, by being pushed down past the spring pawl 52, as necessary, and intermediate compensation being given by the compensating tip 51 which is spring urged by spring 51a. The portion 51 is suitably supported along 51a in a bore. As the table 35 raises and then lowers, its motion through slotted link 38 operates a ratchet pawl 38a against ratchet wheel 38b and in lowering thereby turns the feed roller 39 suitably to apply adhesive to a sufficient sealing portion of the uppermost sheet which is started in contact against and is being wound onto the tube on the mandrel 2. The return throw of the ratchet pawl 38a may be accomplished by a spring 38d whose tension may be adjusted by clamping its anchoring bolt at the point desired in the slot of the bracket 38c. The smoothing roller 40, raised into position by the spring 44b holds an even pressure against the rapidly rotating tube, and the cover is smoothly applied. The ejector collar 25 thereupon moves to slide the tubes ahead of it further along the mandrel, clearing the positions for the further stage of operations.

Other modes of applying the principle of the invention may be employed, change being made as regards the details described, provided the features stated in any of the following claims, or the equivalent of such, be employed.

I therefore particularly point out and distinctly claim as my invention:

1. In tube making apparatus, a mandrel having a free end permitting discharge of tubes formed, means for rotating the mandrel, means for applying adhesive to a web of cellulose, means

for winding the latter convolutely on the mandrel, means for severing the web in sufficient length for a tube, means for compacting the tube, means for surfacing the tube including a feed table for a stack of cover sheets and means for applying adhesive to the topmost sheet thereof and means for stepwise raising the table to contact such topmost sheet with the tube before winding the sheet on the tube, and means for pushing the wound tubes from the winder means to the surfacing means and to discharge by stages.

2. In tube making apparatus, a mandrel having a free end permitting discharge of tubes formed; a shaft for rotating the mandrel; means for applying adhesive to a web of cellulose; a feed table passing the cellulose web to the mandrel; gripping means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built, means for adjusting the swing of said roller relative to the mandrel; timing cam means for operating said roller to and from the mandrel; tube-finishing means including a vertically movable table for supplying final cellulose layer material to the tube, a gluing roller cooperating with said table, means controlled by the movement of the table for turning said roller, a guard finger on said table for restricting the sheet feed, a resilient release pawl allowing progressive descent of the guard finger, a spring-supported compensating tip on said guard finger; timing cam means for operating said table; and a smoothing roller movable to and away from the mandrel, spring means for urging the roller toward the mandrel, and cam means for withdrawing the roller in timed relation to the sheet feed from said table.

3. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web

- detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built, means for adjusting the swing of said roller relative to the mandrel; timing cam means for operating said roller to and from the mandrel; tube-finishing means including a vertically movable table for supplying final cellulose layer material to the tube, a gluing roller cooperating with said table, means controlled by the movement of the table for turning said roller, a guard finger on said table for restricting the sheet feed, a resilient release pawl allowing progressive descent of the guard finger, a spring-supported compensating tip on said guard finger; timing cam means for operating said table; and a smoothing roller movable to and away from the mandrel, and cam means for withdrawing the roller in timed relation to the sheet feed from said table.
4. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built, means for adjusting the swing of said roller relative to the mandrel; timing cam means for operating said roller to and from the mandrel; tube-finishing means including a vertically movable table for supplying final cellulose layer material to the tube, a gluing roller cooperating with said table, a guard finger on said table for restricting the sheet feed, a resilient release pawl allowing progressive descent of the guard finger; timing cam means for operating said table; and a smoothing roller movable to and away from the mandrel, and cam means for withdrawing the roller in timed relation to the sheet feed from said table.
5. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built, means for adjusting the swing of said roller relative to the mandrel; timing cam means for operating said roller to and from the mandrel; tube-finishing means including a vertically movable table for supplying final cellulose layer material to the tube, a gluing roller cooperating with said table, a guard finger on said table for restricting the sheet feed, a resilient release pawl allowing progressive descent of the guard finger; timing cam means for operating said table; and a smoothing roller movable to and away from the mandrel, and cam means for withdrawing the roller in timed relation to the sheet feed from said table.
6. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built; timing cam means for operating said roller to and from the mandrel; tube-finishing means including a vertically movable table for supplying final cellulose layer material to the tube, a gluing roller cooperating with said table, a guard finger on said table for restricting the sheet feed, a resilient release pawl allowing progressive descent of the guard finger; timing cam means for operating said table; and a smoothing roller movable to and away from the mandrel, and cam means for withdrawing the roller in timed relation to the sheet feed from said table.
7. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built; timing cam means for operating said roller to and from the mandrel; tube-finishing means including a vertically movable table for supplying final cellulose layer material to the tube, a gluing roller cooperating with said table, a guard finger on said table for restricting the sheet feed, a resilient release pawl allowing progressive descent of the guard finger; timing cam means for operating said table; and a smoothing roller movable to and away from the mandrel, and cam means for withdrawing the roller in timed relation to the sheet feed from said table.

7. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web 10 detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built; timing cam means for operating said roller to and from the mandrel; tube-finishing means including a vertically movable table for supplying final cellulose layer material to the tube, a gluing roller cooperating with said table, a guard finger on said table for restricting the sheet feed, a resilient release pawl 15 allowing progressive descent of the guard finger; and timing cam means for operating said table.
8. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web 20 detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built; timing cam means for operating said table; and timing cam means for operating said table.
9. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built; and means for operating said roller to and from the mandrel.
10. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built; and means for operating said roller to and from the mandrel.
11. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an oscillatable gripper member provided with gear teeth, pinion means engaging therewith, a pinion shaft in a hollow bore of the mandrel shaft for operating the pinion means, a pin carried by said pinion shaft, a transverse camming slot in the mandrel shaft receiving said pin, a sleeve axially reciprocable on the mandrel shaft, an angularly-directed camming slot in said sleeve, a lever for reciprocating said sleeve, and a cam for operating said lever; means for reciprocating said feed table to and from the mandrel; an anti-friction roller mounting for said feed table in association with slot-means for limiting the motion range; a web detent and slitter and resilient gripper finger on said table; a pressure arm for said gripper finger and an operating arm and de-centering spring connected therefrom to the table for holding the pressure arm in on or off positions; cut-off means including a vertically movable shear blade, and a timing cam and connections for operating said blade; a swingable roll-down roller for smoothing the tube as built; and means for operating said roller to and from the mandrel.

- reciprocating said sleeve, and a cam for operating said lever; means for reciprocating said feed table to and from the mandrel; an anti-friction roller mounting for said feed table in association with slot-means for limiting the motion range; a web 5 detent and slitter and resilient gripper finger on said table; a pressure arm for said gripper finger and an operating arm and de-centering spring connected therefrom to the table for holding the pressure arm in on or off positions; and cut-off 10 means including a vertically movable shear blade, and a timing cam and connections for operating said blade.
12. In tube making apparatus, a mandrel having a free end permitting discharge of tubes formed; a shaft for rotating the mandrel; means for applying adhesive to a web of cellulose; a feed table passing the cellulose web to the mandrel; gripper means in said mandrel including an 15 oscillatable gripper member provided with gear teeth, pinion means engaging therewith, a pinion shaft in a hollow bore of the mandrel shaft for operating the pinion means, a pin carried by said pinion shaft, a transverse camming slot in 20 the mandrel shaft receiving said pin, a sleeve axially reciprocable on the mandrel shaft, an angularly-directed camming slot in said sleeve, a lever for reciprocating said sleeve, and a cam for operating said lever; means for reciprocating 25 said feed table to and from the mandrel; an anti-friction roller mounting for said feed table in association with slot-means for limiting the motion range; a web detent and slitter and resilient gripper finger on said table; a pressure arm for 30 said gripper finger and an operating arm and de-centering spring connected therefrom to the table for holding the pressure arm in on or off positions; and means for cutting the web.
13. In tube making apparatus, a mandrel having a free end permitting discharge of tubes formed; means for rotating the mandrel; means for supplying cellulose sheet material to the mandrel, including a vertically movable table, a guard finger on said table for restricting the sheet feed, a resilient release pawl allowing progressive descent of the guard finger; and means for operating said table.
14. In tube making apparatus, a mandrel having a free end permitting discharge of tubes formed; a shaft for rotating the mandrel; means for feeding a web of cellulose to the mandrel; tube-finishing means including a vertically movable table for supplying final cellulose layer material to the tube, a gluing roller cooperating with said table, a guard finger on said table for restricting the sheet feed; and timing cam means for operating said table.
15. In tube making apparatus, a mandrel having a free end permitting discharge of tubes formed; means for rotating the mandrel; means for supplying cellulose sheet material to the mandrel, including a vertically movable table, a guard finger on said table for restricting the sheet feed, a spring-urged compensating tip in said guard finger, a resilient release pawl allowing progressive descent of the guard finger; and means for operating said table.
16. In tube making apparatus, a mandrel having a free end permitting discharge of tubes formed; means for rotating the mandrel; means for supplying cellulose sheet material to the mandrel, including an intermittently vertically movable table, a guard finger on said table for 70
- restricting the sheet feed, a resilient release pawl allowing progressive descent of the guard finger; spring means for operating said table; an adhesive-applying roller above said table to be engaged by the topmost sheet of the stack thereon; a ratchet-drive for said roller, including a lost-motion link actuated by said table for operating said ratchet drive; and a smoothing roller engageable against the sheet supplied to the mandrel. 5
17. In tube making apparatus, a mandrel having a free end permitting discharge of tubes formed; means for rotating the mandrel; means for supplying cellulose sheet material to the mandrel, including an intermittently vertically movable table, a guard finger on said table for restricting the sheet feed, a resilient release pawl allowing progressive descent of the guard finger; spring means for operating said table; an adhesive-applying roller above said table to be engaged by the topmost sheet of the stack thereon; a ratchet-drive for said roller, including a lost-motion link actuated by said table for operating said ratchet drive; a smoothing roller engageable against the sheet supplied to the mandrel; and cam means for intermittently controlling 10 said smoothing roller. 15
18. In tube making apparatus, a mandrel having a free end permitting discharge of tubes formed; means for rotating the mandrel; means for supplying cellulose sheet material to the mandrel, including an intermittently vertically movable table, a guard finger on said table for restricting the sheet feed, said guard finger being mounted for progressive descent in accordance 20 with the height of the stack of sheets; an adhesive-applying roller above said table to be engaged by the topmost sheet of the stack thereon; means for driving said adhesive-applying roller in timed relation with the movement of the table; a smoothing roller engaged to the sheet supplying the roller; and means for intermittently applying said last-named roller. 25
19. In tube making apparatus, a mandrel having a free end permitting discharge of tubes formed; means for rotating the mandrel; means for supplying cellulose sheet material to the mandrel, including a vertically movable table, a guard finger on said table for restricting the sheet feed, a spring-urged compensating tip on said guard finger; an adhesive-applying roller above said table to be engaged by the topmost sheet of the stack thereon; a ratchet drive for said roller; a lost-motion link for operating said ratchet-drive; a smoothing roller engageable against the sheet supplied to the mandrel; and means for intermittently controlling said last-named roller. 45
20. In tube making apparatus, a hollow mandrel having a free end permitting discharge of tubes formed; means for rotating the mandrel, including a hollow driving shaft; means for supplying cellulose tube-forming material to the mandrel; gripper means in said mandrel including an oscillatable gripper member provided with gear teeth, pinion means engaging said gear teeth, a pinion shaft extending axially in said hollow driving shaft and said mandrel for operating the pinion means, said pinion shaft being the same for both small and large mandrel sizes; a continuous hollow passage through said pinion shaft from said hollow driving shaft; and means for intermittently turning said pinion shaft. 50 55
